Patented Dec. 8, 1925.

1,564,218

UNITED STATES PATENT OFFICE.

HERBERT H. DOW, OF MIDLAND, MICHIGAN, ASSIGNOR TO THE DOW CHEMICAL COMPANY.

METHOD OF CONTROLLING CHEMICAL REACTIONS.

No Drawing.

Application filed December 8, 1920. Serial No. 429,081.

To all whom it may concern:

Be it known that I, HERBERT H. Dow, a citizen of the United States, and a resident of Midland, county of Midland, and State of Michigan, have invented a new and useful Improvement in Methods of Controlling Chemical Reactions, of which the following is a specification, the principle of the invention being herein explained and the best mode in which I have contemplated applying that principle, so as to distinguish it from other inventions.

The present invention relating as indicated to methods of controlling chemical reactions, has more particular regard to the control of reactions in so-called fusion processes, and especially to the control of the temperatures of such reactions. While, within the range indicated, the invention has more or less general adaptability, I have discovered in applying the same to the manufacture of indoxyl according to the original process of Heumann and subsequent improvements of such process, that new and unexpected results are secured of very considerable importance in the commercial production of synthetic indigo. The invention will accordingly be described by a specific reference to a method of making indoxyl and derivatives wherein a phenyl-glycine body is intermixed with a caustic alkali melt, the new results accomplished including, in addition to the control of the temperature of the melt in such fashion as to prevent any undue decomposition of the phenyl-glycine or equivalent body, the blanketing of the melt and of the un-reacted phenyl-glycine body against oxidation. At the same time I am able to maintain such body in more completely disseminated condition in the fusion mixture, thus insuring a uniformly satisfactory product.

With regard to the provision of a blanketing medium for the melt, which is an incidental feature in the present case, I should remark that I have heretofore described and claimed (see my co-pending application filed August 31, 1918, Serial No. 252,225) a method of blanketing with hydrocarbon vapor the fusion mixture in a process involving the fusion together of materials so as to produce a chemical reaction between the latter, and the present improved method or process is designed among other things to achieve this same result, but in a different manner.

To the accomplishment of the foregoing and related ends, the invention then consists of the steps hereinafter fully described and particularly pointed out in the claims, the following description setting forth in detail one approved mode of carrying out the invention, such disclosed mode, however, constituting but one of the various ways in which the principle of the invention may be used.

As previously indicated, the making of indoxyl and its derivatives will conveniently serve by way of illustration of my improved method or process of controlling chemical reactions. Heumann's original process for the manufacture of synthetic indigo by the fusion of phenyl-glycine with caustic potash did not prove commercially practicable because of the small yield obtained and numerous modifications of such process have since been proposed, some by Heumann himself (see U. S. Patent No. 617,652) for increasing the yield. Various theories moreover have been set forth in explanation of this unsatisfactory result, Friedlander for example suggesting (Fortschritte der Theerfarben-Industrie Part II, p. 100) that such poor yield is due to the fact that the caustic alkalies destroy the indoxyl formed and break up the glycine before it undergoes transformation into indoxyl. In accordance with this theory dehydrating agents have been added to the caustic potash or caustic soda or mixture of the two constituting the bulk of the fusion mixture, to assist the reaction and allow the temperature of the melt to be reduced below that which had to be employed when caustic alkalies alone were used. Despite the fact that by such means a yield of indoxyl as high as 50 per cent of the weight of glycine has been achieved, the latter is so readily decomposed at the temperature at which it is introduced into the melt that a serious loss is entailed and commercial use of such modified processes has been correspondingly restricted.

As a matter of fact, such decomposition of the phenyl-glycine body begins at 300° centigrade or even lower, and at 320° centigrade is substantially complete, and the reaction will only take place in molten caustic, and the caustics in the proportion in which they are ordinarily used require to be raised to a temperature of approximately 250° if the melt is to remain sufficiently fluid.

There is thus only a very narrow range permitted and when it is further recalled that the increase in temperature during the heat of reaction due to the exothermic character 5 of the latter may equal or exceed this range, the difficulties encountered in controlling the reaction will be obvious.

I have discovered that by mixing with the phenyl-glycine body before it is added to the 10 fused caustics a neutral hydrocarbon oil such for example as commercial kerosene which contains constituents that boil at a temperature between that at which such caustics are molten and that at which such decomposition 15 of the phenyl-glycine body sets in, the cooling effect of the evaporation of such oil will offset the heat of reaction and an approximately constant temperature can thus be maintained in the melt. The importance of 20 this has already been sufficiently emphasized, but an additional advantage follows in that by preventing an increase in temperature due to the reaction it is possible to operate with a much smaller percentage of 25 caustic potash than has heretofore been the case, such caustic potash being the more expensive of course of the two ingredients of the melt, and for that matter the amount of both may be decreased.

30 Thus, whereas in the method of making indoxyl described in United States Letters Patent Reissue No. 14,364 to L. E. H. Cone, dated September 25, 1917, 60 parts of potassium hydroxide and 40 parts of sodium hydroxide are specified, it has been found feasible by the present improved method to reduce the caustic potash to less than ten percent, the proportion of caustic soda being correspondingly increased. To such mixture of caustic potash and soda I preferably add, as described in said Reissue Letters Patent, quicklime and metallic sodium in approximately the proportions set forth in the specific example in said patent and the 40 amount of phenyl-glycine potassium (or sodium) salt employed is likewise in the same proportion; in fact, the procedure will follow exactly that of the patent in question except for the fact that the phenyl-glycine 45 salt before it is added to the fusion mixture consisting of such caustic potash, caustic soda, quicklime and sodium, is thoroughly wetted with kerosene or equivalent neutral hydrocarbon oil. The amount of such oil 50 employed will depend upon the size of the batch and other operative conditions; where, as in commercial practice, a melt weighing altogether approximately 3000 pounds or more is made up, the phenyl-glycine salt 55 may be wetted with kerosene until it will flow more or less freely, approximately equal amounts by weight of the phenyl-glycine salt and kerosene being found satisfactory.

60 In addition to keeping down the temperature of the fused mass to a point below that

at which decomposition of the phenyl-glycine body occurs at least in harmful degree, the neutral hydrocarbon oil protects such body against oxidation and upon volatilizing will find its way to the surface and there 70 form a blanketing medium for the melt exactly in the same way as though such oil were simply dropped onto the surface as proposed in the fusion process described in my co-pending application above referred to. 75 Such blanketing vapor protects the fusion mixture and particularly any phenyl-glycine that may be floating on its surface from oxidation if the atmosphere above the fusion should happen to contain a small amount of oxygen. Moreover the phenyl-glycine thus wetted with oil mixes much more readily with the caustic bath so that considerably less agitation is necessary than where dry phenyl-glycine is used. The wetted material 80 comes into better contact with the molten caustic and the vaporization of the oil tends to disintegrate any lumps or agglomerated masses of the material.

Even in the case of the specific reaction 90 involved in the manufacture of indoxyl, different oils will be found to fulfill satisfactorily the requirements, in addition to kerosene which has been specifically mentioned. Thus, other mineral oils, i. e. petroleum distillates, of the same series, and various coal-tar distillates, particularly those members of the benzene series which are neutral in character towards the phenyl-glycine body and 95 caustic ingredients and which volatilize at the proper temperature, may be employed. The preferred range of temperature at which the fusion should be held during the reaction is 230° and 285° centigrade, and the 100 amount of any particular oil employed may be readily determined from a knowledge of its boiling point and latent heat of vaporization taken in conjunction with the amounts of the other ingredients of the melt.

For that matter, since heat of course is 110 absorbed in the change of a body from solid to liquid form just as well as in changing from a liquid to a gaseous form, substances that are solid at normal temperatures may, if otherwise suited, be 115 employed to secure the control of temperature of the melt to a certain extent, as well as the desired dissemination of the material being reacted upon in such melt. Thus, for example, paraffine can be used in the specific case cited although not as satisfactorily as kerosene, especially since the latter upon being volatilized rises to the surface 120 of the melt and forms a blanketing medium over the same. So, too, by introducing the proper amount of solid, i. e. unmelted caustic, along with the phenyl-glycine body, the condition of the melt can be controlled in an 125 analogous manner, the heat of the reaction being absorbed by the conversion of such ad-

ditional caustic from such solid to molten condition.

- It will be understood that the term phenyl-glycine body connotes not merely the specific 5 phenyl-glycine salt hereinbefore mentioned, but other derivatives and homologues of phenyl-glycine, including the esters and anhydrides of phenyl-glycine and its homologues, phenyl-glycine and its homologues, 10 and like bodies. Moreover, it will be evident that the underlying principle of controlling chemical reactions by the inclusion in the reaction zone of a neutral substance adapted to change its physical form, 15 with attendant absorption by heat at a temperature below that at which either an ingredient or the product is decomposed, is of general applicability and not limited to so-called fusion processes.
- 20 Other modes of applying the principle of my invention may be employed instead of the one explained, change being made as regards the method herein disclosed, provided the step or steps stated by any of the following claims or the equivalent of such 25 stated step or steps be employed.

I therefore particularly point out and distinctly claim as my invention:—

1. In a method of making indoxyl and its 30 derivatives, the steps which consist in intermixing a phenyl-glycine body with a caustic alkali melt, and including in the mixture a neutral hydrocarbon oil adapted to be vaporized at a temperature between that at which 35 such caustic alkali is molten and that at

which decomposition of such phenyl-glycine body sets in.

2. In a method of making indoxyl and its derivatives, the steps which consist in intermixing a phenyl-glycine body with a caustic 40 alkali melt, and including in the mixture a neutral mineral oil having a boiling point below that at which decomposition of such phenyl-glycine body sets in.

3. In a method of making indoxyl and its 45 derivatives, the steps which consist in intermixing a phenyl-glycine body with a caustic alkali melt, and including kerosene in the mixture.

4. In a method of making indoxyl and its 50 derivatives, the steps which consist in wetting a phenyl-glycine body with a neutral hydrocarbon oil, and then intermixing the same with a caustic alkali melt.

5. In a method of making indoxyl and its 55 derivatives, the steps which consist in wetting a phenyl-glycine body with a mineral oil having a boiling point below that at which decomposition of such phenyl-glycine body sets in; and then intermixing the same 60 with a caustic alkali melt.

6. In a method of making indoxyl and its derivatives, the steps which consist in wetting a phenyl-glycine body with kerosene; and then intermixing the same with a caustic 65 alkali melt.

Signed by me this 4th day of December, 1920.

HERBERT H. DOW.
